UNITED STATES PATENT OFFICE.

GEORGE EDWARD NYE, OF PHILADELPHIA, PENNSYLVANIA, ASSIGNOR OF ONE-HALF TO EDWARD TREDICK, OF SAME PLACE.

CAM-ADJUSTING MECHANISM FOR CIRCULAR-KNITTING MACHINES.

SPECIFICATION forming part of Letters Patent No. 416,488, dated December 3, 1889.

Application filed January 9, 1889. Serial No. 295,840. (No model.)

To all whom it may concern:

Be it known that I, GEORGE EDWARD NYE, of Philadelphia, in the county of Philadelphia and State of Pennsylvania, have invented certain Improvements in Cam-Adjusting Mechanism for Circular-Knitting Machines, of which the following is a specification.

The present invention relates to that class of machines in which a series of horizontal reciprocating needles disposed radially in a so-called dial-plate are used in connection with a series of vertical reciprocating needles mounted in a revolving cylinder and operated by stationary adjustable cams.

It relates to improved means for effecting the vertical adjustment of the cams which control the vertical needles.

As the machine may be in all other respects of ordinary construction, I have shown only such parts as are necessary to an understanding of my improvements.

In the accompanying drawings, Figure 1 represents a top plan view of my machine. Fig. 2 is a side elevation of the same with a portion shown in vertical section on the line $l l$ of Fig. 1. Fig. 3 is a vertical section through one side of the cylinder and adjacent parts on the line xx of Fig. 1, the dial-plate being omitted. Fig. 4 is an inside face view of a portion of the cam-ring and adjacent parts. Fig. 5 is a top plan view of the same. Fig. 6 is a perspective of the external cam-adjusting ring. Fig. 7 is a view of one of the cam-adjusting levers and its adjustable bearings. Fig. 8 is a perspective view of one of the adjustable needle-depressing cams. Fig. 9 is a side elevation showing a modified form of the cam-adjusting ring. Fig. 10 is a cross-section through one side of the frame, showing the adjusting devices applied to a needle-lifting cam.

Referring to the drawings, A represents a stationary bed or base-plate provided on opposite sides with rigid standards a , which give support to a cross-bar or yoke a' .

B represents the rotary needle-cylinder, supported by the annular gear or "gear-ring," as it is commonly termed b , seated in

the base-plate and sustained by the underlying plate b' , so that it may revolve with entire freedom.

C represents the so-called "dial," lying in a horizontal position within the upper end of the cylinder. It is composed, as usual, of the dial-plate proper c , to sustain the needles, and the overlying cam-plate c' . These parts are constructed in all respects in the ordinary manner, and as they form no part of the present invention a detailed description thereof is unnecessary. The dial as a whole is suspended from the cross-bar a' by a bolt c^2 , screwed or otherwise fixed rigidly into the bar, as usual. I provide the upper ends of the standards a and the under face of the cross-bar a' with extended flat faces in a true horizontal position, so that the cross-bar may be shifted horizontally upon the standards without permitting it to rock or tip in any direction. I provide the ends of the bar with vertical holes a^2 , and through these holes I pass the vertical bolts a^3 , of a diameter less than the holes, either with or without the application of intermediate plates or washers a^4 beneath the heads of the bolts. When the bolts are loosened, the cross-bar may be shifted at either end, so as to bring the dial-plate in the precise position required, after which by simply tightening the bolts the parts may be secured rigidly in place.

I do not claim herein the above-described mode of securing the cross-bar, the same being the subject of a separate application for patent executed April 20, 1889.

D D, &c., represent a series of stationary needle-depressing cams grouped at suitable distances apart around the cylinder in position to act upon the heels of the needles, as in other machines in general use. The means for supporting and adjusting these cams is the leading feature of my invention. The cams are seated against the inner face of an annular wall or ring a^5 , rising rigidly from the bed plate or frame. They may be guided thereon in any ordinary or suitable manner which will permit of their rising and falling. The preferred construction is that shown in the drawings, in which each cam is provided

with a vertical rib d , seated in a corresponding groove in the wall, and the wall provided with vertical ribs d' , which bear against the vertical ends of the cams, as plainly shown in Figs. 4 and 5. The ribs d' are inserted and fixed rigidly in grooves in the supporting-wall. This construction is advantageous in that it permits the frame to be cheaply finished in a lathe, after which the ribs d' are applied thereto.

Each cam is mounted on the inner end of a supporting and adjusting lever, which extends outward through the supporting-wall a^5 into an oblique or spiral groove in an external ring F , arranged to be revolved at will around the outside of the wall a^5 . The form of this ring and its lever-operating grooves f is plainly shown in Fig. 6. The levers may be supported and connected to the cams in any appropriate manner. I prefer, however, to insert their ends into holes e^5 , formed in the cams for the purpose, as shown more particularly in Figs. 3 and 8, and to construct the supports in the manner shown in detail in Figs. 3 and 7. In this construction each lever is formed at the middle with a spheroidal portion e^6 , seated at its under side in a cup or bearing e , sustained by a spring e' . A screw e^2 , cupped at its lower end, bears on top of the portion e^6 . The spring forces the bearing-cup upward, maintaining a close connection between the parts and compensating automatically for wear. By turning the screw downward the fulcrum-point of the lever may be lowered and thus the height of the cam altered, so as to bring the entire series of cams on a common level. The bearing-cups and the springs e' are all seated in a hole drilled downward into the wall a^5 of the bed-plate.

The external ring F is commonly provided with a handle f' , or other appropriate means by which it may be turned, and is also provided with a series of graduations f^2 to be read in connection with a mark or index f on the supporting-wall or other stationary part of the machine. When the ring is turned in one direction, it depresses the outer ends of the levers and causes the entire series of cams D to be raised simultaneously and equally, and when turned in the opposite direction it depresses the cams in like manner. In this way the operator is enabled instantly to vary the distance to which the needles are depressed, so as to control the tightness of the stitch or to prevent the casting of the stitches from latched needles.

In order to effect the elevation of the needles a series of lifting-cams G are mounted on the inside of the wall a^5 . These lifting-cams, which form no part of my invention, may be in ordinary form, either stationary or adjustable, as preferred.

I have represented in the drawings a machine for eight sets of cams and a corresponding number of thread-guides, whereby the

machine is enabled to lay eight threads into the fabric successively at each revolution in a manner practiced in ordinary machines and familiar to every person skilled in the art. Of course the number of cams may be increased or diminished at will.

To prevent accidental rotation of the cam-adjusting ring F , I provide a set-screw f^4 , passing through a horizontal slot f^8 in the ring into the stationary wall of the frame.

It will be understood that the essence of my invention as regards the adjustment of the cams consists in the employment of levers which support the individual cams in connection with a rotary ring having inclined slots or bearings to operate the entire series of levers, and obviously the details are susceptible of any modification within the range of mechanical skill, provided the mode of operation hereinafter described is retained.

While I prefer to provide the ring F with the oblique lever-controlling slots, the slots may be arranged horizontally in the ring, as shown in Fig. 9, and the ring adapted to rise and fall bodily as it is turned, by providing it with oblique slots f^4 , to receive stationary supporting-pins f^5 . The ring thus adapted to rise and fall actuates the lever in substantially the same manner and with the same effect as the ring shown in Fig. 6.

While my cam-adjusting device is designed mainly for use in connection with the upper or needle-depressing cams it may be applied in like manner to adjust the lower or needle-elevating cams, as illustrated in Fig. 8.

I am aware that vertically-adjustable cams have been operated in a knitting-machine by means of external rings connecting directly with studs projecting rigidly from the cams, and to such combination, which is open to various practical objections, I lay no claim.

Having thus described my invention, what I claim is—

1. In a knitting-machine, the combination of a wall or support, a series of levers mounted therein, needle-actuating cams mounted on the inner ends of the levers, and a rotary adjusting-ring common to the series of levers, said parts constructed and arranged substantially as herein described and shown.

2. The frame or bed having the annular wall or support a^5 , the needle-operating cams connected by upright guides to said wall, the levers mounted in the wall and engaging the respective cams, and the external rotary ring provided with the oblique grooves to receive the ends of the levers, whereby the rotation of the ring is caused to raise or lower the cams in unison.

3. In combination with a needle-operating cam D , its adjusting-lever, and a lever-adjusting ring, the lever-support consisting of a bearing e , a supporting-spring e' , and a bearing-screw e^2 , arranged substantially as shown.

4. In combination with the cam and an ad-

justing-ring, the intermediate lever having the spheroidal bearing-surface and the cupped supports therefor.

5. In a knitting-machine, the series of needle-actuating cams, an external ring, as described, and intermediate levers connecting the ring with the respective cams, in combination with independent vertically-adjust-

able bearings for the respective levers, whereby the cams may be independently adjusted in relation to each other and the ring.

GEORGE EDWARD NYE.
